[57] CLAIM

[21] Appl. No.: 247,876

The ornamental design for a motorcycle tire, as shown and described.

[22] Filed: Mar. 26, 1981

DESCRIPTION

[51] Int. Cl. ..... D12—15
[52] U.S. Cl. D12/146
[58] Field of Search ..... D12/145—151;
152/209 R, 209 NT, 209 D

FIG. 1 is a perspective view of a motorcycle tire showing our new design, it being understood that the tread design is repeated throughout the circumference of the tire as shown schematically in solid lines, the opposite side being substantially the same as that shown;
FIG. 2 is a front elevational view thereof;
FIG. 3 is a side elevational view thereof.

FIG. 1

FIG. 2

FIG. 3
